UNITED STATES PATENT OFFICE.

CHARLES H. AYARS, OF SALEM, NEW JERSEY, ASSIGNOR TO AYARS MACHINE COMPANY, OF SALEM, NEW JERSEY.

CAN-FILLING MACHINE.

Application filed April 1, 1922. Serial No. 548,563.

To all whom it may concern:

Be it known that I, CHARLES H. AYARS, a citizen of the United States, residing at Salem, in the county of Salem and State of New Jersey, have invented certain new and useful Improvements in Can-Filling Machines, of which the following is a specification.

My invention relates to canning machines and more especially to mechanism for imparting to the hopper an oscillating or vibrating motion to insure the discharge from the hopper of all its contents.

In the use of canning machines the materials to be canned are sometimes viscous or sticky and have a tendency to adhere to the walls of the hopper. When working with such materials or when emptying the hopper to change goods or clean the hopper it is highly desirable to have mechanical means for jarring the adhering grains from the hopper and it is the object of my invention to provide simple and efficient mechanism for that purpose.

This object I attain in the following manner, reference being had to the accompanying drawings in which—

Figure 1 is a side elevation, partly in section of a canning machine embodying my invention.

Figure 2 is a front elevation partly in section and with the hopper removed.

Figure 3 is a top plan view, with the hopper removed, showing the mechanism for imparting vibrating motion to the hopper in its inoperative position, and

Figure 4 is a like view showing said mechanism in its operative position.

I have shown and described my invention as applied to the type of canning machine shown in my co-pending application Serial No. 382,368, filed May 18, 1920.

Referring to the drawings, 10 represents the frame or supporting structure of a canning machine. In this frame are mounted a driving shaft 11 on which is a bevel gear 12 meshing with a bevel gear 13 fixed to the lower end of a vertical shaft 14. A measuring wheel 15 and a distributing wheel 16 are keyed to shaft 14. These parts are disclosed in my co-pending application above referred to and a description of this construction and mode of operation is not essential to an understanding of the present invention.

In this case a hopper 17 is carried by a plate 18 provided with a flange 19 into which the lower end of the hopper is fitted. The plate 18 may be supported in any suitable manner but is here shown as mounted upon the top section of the measuring wheel 15 and provided with a boss 20 encircling a boss 21 which extends upwardly from the measuring wheel and which encircles shaft 14. By this construction the hopper carrying plate is capable of rotary movement relative to the measuring wheel and vertical shaft. The hopper plate 18 is provided with a fixed arm 22 having at its free end a lug 23 preferably of cylindrical form. A bell crank lever 24 is fulcrumed upon any suitable fixed part of the machine as at 25. One arm, 24^a, of the lever is provided at its free end with a U-shaped socket 26 adapted to embrace the lug 23 on the arm 22 of the hopper plate, and the other arm, 24^b, carries a roller 27. A cam 28, having one or more abrupt shoulders 29, is fixed to the driving shaft 14 and positioned for engagement with roller 27 on the crank arm. A spring 30 is connected with the lever arm 24^b at 31 and with a fixed part of the machine as at 32, the spring being adapted, when the vibrating mechanism is operated, to hold the roller in engagement with the cam.

In operation, as the driving shaft rotates a shoulder on the cam engages with the roller on the bell crank lever and abruptly moves the lever in one direction; this imparts motion to the U-shaped arm at the other end of the lever, and, through lug 23 and arm 22 to the hopper plate 18 and hopper 17. As the cam rotates the spring restores the lever arm and hopper to their original position and the operation is repeated. The result is a series of abrupt oscillations of the hopper upon the shaft 14 as an axis which tends to free the hopper of any material which would otherwise adhere thereto. The oscillatory motion should not be so extensive as to interfere with the proper discharge of the materials into the measuring vessels.

Inasmuch as some materials feed clearly without the vibrating or jarring action it is advisable to provide means for throwing the vibrating mechanism out of commission without interfering with the operation of the other parts of the machine. This may be

readily effected by means of a lever 33 fulcrumed at 34 and having a bent arm 35 adapted to engage with the arm 24^a of the bell crank lever 24 and throw it in the direction of the cam 28 thereby throwing the roller 27 in the reverse direction and out of engagement with the cam.

The extent of oscillatory movement of the hopper should not be so great as to interfere with the proper discharge of the material into the measuring receptacles, and it should be noted that the extent of movement of the hopper is limited by the throw of the actuating lever.

While I have described my invention as taking a particular form, it will be understood that the various parts of my invention may be changed without departing from the spirit thereof, and hence I do not limit myself to the precise construction set forth, but consider that I am at liberty to make such changes and alterations as fairly come within the scope of the appended claims.

Having thus described my invention, what I claim as new and desire to secure by Letters Patent is:—

1. In a can filling machine, the combination of a driving member; a hopper; a rotatable plate carrying the hopper; connections between the driving member and the rotatable plate adapted to impart oscillatory motion to the plate, and means for engaging or disengaging said mechanism, substantially as described.

2. In a can filling machine, the combination of a hopper; a rotatable plate carrying the hopper; a lever adapted to engage at one end with the rotatable plate; a rotatably mounted cam adapted to actuate the other end of the lever, thereby imparting oscillatory motion to the hopper, and means for holding the lever in operative relation to the cam; substantially as described.

3. In a can filling machine, the combina-

tion of a hopper; a rotatable plate carrying the hopper; a lever adapted to engage at one end with the rotatable plate; a rotatably mounted cam adapted to actuate the other end of the lever, thereby imparting oscillatory motion to the hopper, and means for holding the lever in operative relation to the cam, and means for throwing the lever out of operative engagement; substantially as described.

4. In a can filling machine, the combination of a hopper; a rotatable plate carrying the hopper; a bell crank lever having an arm arranged to engage with the rotatable plate; a rotatable cam adapted to actuate the other arm of the lever, thereby imparting oscillatory motion to the hopper, and means for holding the lever in operative relation to the cam; substantially as described.

5. In a can filling machine, the combination of a driving member; a movably mounted hopper; a lever adapted to impart oscillatory motion to the hopper; a rotatably mounted cam adapted to actuate the lever, and a second lever adapted to throw the first named lever out of or into operative engagement, substantially as described.

6. In a can filling machine, the combination of a hopper; a rotatable plate carrying the hopper; a bell crank lever having one arm adapted to engage with the rotatable plate; a roller carried by the other arm of the lever; a rotatable cam adapted to engage with the roller and actuate the lever, and means for holding the roller in engagement with the cam; substantially as described.

In testimony whereof I have signed my name to this specification in the presence of two subscribing witnesses.

CHARLES H. AYARS.
